UNITED STATES PATENT OFFICE

EUGENE J. RAY, OF BEVERLY, MASSACHUSETTS, ASSIGNOR TO UNITED SHOE MACHINERY CORPORATION, OF PATERSON, NEW JERSEY, A CORPORATION OF NEW JERSEY

COATING APPARATUS

Application filed May 9, 1930. Serial No. 451,151.

My invention relates to apparatus for applying a coating to work-pieces. An example of the work for which the apparatus is particularly adapted is furnished by the blanks of felt or like material for box-toes of shoes, which blanks are to have placed upon them a heavy pitchy substance, which, after it has set, may later be softened by heat to cause the blanks to conform to the toes of 10 shoes being lasted, so they will retain their shape when said pieces have cooled and hardened.

An object of the invention is to coat work of the character just indicated heavily upon one or both sides and by a simple and efficient apparatus. I accomplish this by combining with a tank or receptacle for the coating substance, coating-applying plates or members arranged to contact with opposite sides of 20 the work, together with means for holding the members separated from each other within the coating substance, for moving these members into and out of the substance and, in the last-mentioned position, into contact with interposed work. The applying members are thus capable of receiving from the supply in the receptacle a comparatively thick layer of the coating substance, which is thereafter transferred to the work. I have shown 25 the coating members as carried by oscillatory arms, with each of which co-operates a rotatable actuating member, as a cam, these actuating members imparting to the applying members the desired relative movements. 30 There is preferably associated with the applying members a pressure member co-operating with the work. This pressure member may be mounted and actuated in a manner similar to the applying members. It is shown as heated, to avoid the gathering upon it of the coating substance. By moving the pressure member with one of the applying members toward the work and then maintaining it after the withdrawal of said applying members, the work may be prevented from adhering to one of the latter. Adhesion to the other member may be guarded against by contact of the work with a supporting surface, with which the receptacle 35 is provided. If it is desired to have upon

one side of the work a coating less thick than on the other, a scraper may be mounted in the receptacle, over which scraper each work-piece may be drawn as it is removed from between the applying members. A recess in 55 the front of the receptacle allows the operator to grasp effectively the work-piece for its presentation to and removal from the applying members. The receptacle is preferably heated, to give the necessary fluidity to 60 the coating substance, and the recess also enables the operator to keep his hand away from the hot receptacle-wall, and reduces the danger of burns from spattering of the coating substance. One or more gage members, 65 which, as shown, are adjustable to adapt them to position different sizes of work-pieces, are shown as associated with the receptacle.

In the accompanying drawings illustrating a specific embodiment of the invention, 70

Fig. 1 is a top plan view of my improved apparatus;

Fig. 2, a side elevation looking from the right in Fig. 1, with parts broken away;

Figs. 3 and 4, broken sectional details of 75 the elements more closely associated with the work, these, respectively, showing the work-piece-coating and the work-piece-withdrawing relations; and

Fig. 5 shows a top plan view of the lower 80 and upper applying plates positioned out of alinement with each other.

Assuming that stiffening pieces for the toes of shoes are to be coated, such a piece appears at S in Fig. 1 of the drawings. The toe-portions, prior to welting, are sometimes shaped by being molded under the influence of heat, and it may be desirable to keep the toe comparatively soft, in which case it is convenient to stiffen the pieces S only over a crescent-like area at the front marginal portion. This, after the pieces have been treated with pitch or other thermoplastic substance and molded with applied heat, will sufficiently hold the shape of the toe-portion of the lasted upper, so it need not be wired for the welting operation. 95

For coating work of the character and in the manner described above, I provide a tank 10 for the substance to be applied. This is 100

shown as generally rectangular in horizontal section, is supported upon legs 12 and is adapted to be mounted upon a bench. To keep the contents of this receptacle in condition for application to the work, electrical heating units 14 may be placed at the under side. At the front of the tank is a recess, as appears at 16, for a purpose which will later be made clear. From the rear of the tank, 10 at the opposite side, project arms or brackets 18, 18.

Carried in the outer extremities of the tank-brackets is a horizontal spindle 20, and arranged to turn about this are arms 22, 24 and 26, spaced from one another and held against lateral movement by elongated hubs 28 contacting with one another and by end-collars 30, 30. Secured upon the arm 22 is a lower applying plate 32 (Fig. 2) having its forward, active portion elongated transversely of the tank and extending to the right as viewed in Fig. 5. Above, and vertically aligned with it, is a similar co-operating applying plate 34 carried by and extending 25 to the left of the arm 26. Both plates may be recessed at 36, this depression corresponding substantially in curvature to that of the tank-recess 16. They are connected to their respective supporting arms by relative 30 narrow portions 33 containing perforations 35, which, by allowing the coating substance to pass through them, will prevent it from gathering in such quantities upon the upper surfaces of the plates as to flow over 35 the edges toward the work-piece. Such a flow would tend to deposit an unduly heavy line of the substance along the margin of the coated area. When the toe-stiffening piece is placed in the apparatus between the plates, 40 their areas of contact therewith are as illustrated in Fig. 1, the curve at 36 being approximately concentric to the forward extremity of the piece being operated upon, so a band of substantially uniform width is applied about 45 said extremity. Upon the center arm 24 is a pressure or retaining member furnished by a bar or vertically extending plate 38. The bar appears as corresponding in form to the forward edges of the plates 32 and 34, lying 50 just in front of the latter and spaced from the adjacent wall of the tank, it being movable by its arm into close proximity to the upper edge of a scraper-bar 40, which extends across the tank, to the walls of which it is fastened. 55 Since the coating substance might tend to accumulate upon the lower contact edge of the bar 38, daubing the work outside the area to be coated and causing excessive adhesion to it, I prefer to mount a heating unit 41 in the 60 arm 24 adjacent to said bar. This maintains the gathering substance fluid, so it freely drips off and clears the bar. In horizontal section, the bars 38 and 40 are similar in contour and are vertically aligned. Journaled in 65 the lower part of the brackets 18 is a horizon-

tal shaft 42, upon which are fast three cams 44, one for each of the arms 22, 24 and 26. Rolls 46, rotatable upon the arms, rest on the cams, the contact being maintained either by gravity or by springs 43. The shaft 42 may be rotated by a crank 48 or by power otherwise applied to turn the cams, the shapes of the peripheries of which are designed to impart to the two applying plates and to the pressure-bar the movements of reciprocation at different rates outlined in the statement of operation of the apparatus.

The upper surface 50 of the front wall of the tank is preferably approximately level with the corresponding edge of the bar 40, and this, with two shelves 52, 52 secured to the side walls of the tank, furnish supporting surfaces for the work in the same plane as the surface 50. Upon these supporting surfaces each piece of work is laid for its coating, being correctly located by gages 54, 54 attached to the upper faces of the shelves and arranged for contact with their gagging surfaces of the rear corners of the stiffening pieces S. These pieces may differ in size, and, to properly present them to the applying members, the gages are preferably adjustable. I have shown in each gage a slot inclined at approximately 45° with respect to the longitudinal axis of the apparatus and of the stiffening piece from front to rear when it is in place upon the apparatus. In each of these slots are three enlargements 58. Through each slot passes a pin 60 slidable vertically in a shelf 52, the stem of which will enter the slot, while beneath its upper end or head 64 is a cylindrical portion of such diameter that it will be received only in the slot-enlargements. A spring 66, interposed between the lower extremity of each pin and the under side of the shelf, holds the head and enlarged portion normally down, with the latter in one of the enlargements 58. When it is desired to change the position of a gage, the pin is grasped by the head and raised against the force of the spring, this drawing the enlarged portion out of the slot-enlargement which it has occupied. The gage is then shifted to bring the desired enlargement into alignment with the enlarged portion of the pin, and the head released, so that the spring draws the pin down to lock the gage in its new position. In this adjusting movement, the gage may be guided by a depending vertical pin 68 fixed in the gage and projecting into a slot 56 in the shelf. Slot-and-screw connections 70 between the shelves and tank-walls permit bodily adjustment of the gages longitudinally of the tank.

Considering the operation of the apparatus, the gages being adjusted in accordance with the particular size of toe-stiffening piece or other work to be coated, one of these pieces is laid in a horizontal position upon the surfaces offered at 40, 50 and 52, 52, with its

forward crescent-like portion overhanging the interior of the receptacle. The depression 16 enables the operator to firmly grasp the work-piece without bringing his hand unduly close to the hot wall of the tank. At the time of application of the work, the crank 48 will be at such an angle that the work-engaging elements 32, 34 and 38 are situated as appears in Fig. 2. The previous operation 10 will have supplied the plates with the coating substance, as a result of their immersion in the tank, where it is held in a fluid condition by the heat of the units 14. The bottom plate 32 is at this time beneath the surface 15 of the coating substance, and the upper 34 in its highest position. This leaves the plane of insertion of the work clear, the pressure member 38 being also at its upper limit. With the work in place, the crank is rotated 20 clockwise, as viewed in Fig. 2. The plate 32 rises, and when it has reached an angle with relation to the work approximately the same as that of the plate 34, the latter descends. The pressure member 38 may move somewhat in advance of the plate 34, reaching the work first and holding it against the bar 40. The plates thereupon together engage the opposite sides of the work, transferring to it their loads of the coating substance. This 25 occurs somewhat before the crank has been turned through 180°, the elements being as illustrated in Fig. 3. At the 180° position of the crank, the plates 32 and 34 have separated (Fig. 4), the member 38 remaining down to 30 retain the work from being drawn up by adhesion to the plate 34. Said work cannot follow the plate 32 because of the support provided by the bar 40. The crank is stopped in this position and the work withdrawn. 35 If the operator wishes a lighter coating upon one surface than upon the other, to prevent, for example, the coating substance from striking through the lining of a shoe, he forces the piece, as he pulls it toward him, 40 down against the bar 40. This scrapes the excess from the under side, leaving the upper heavily coated to give the requisite stiffening effect. Continued rotation of the crank, after the piece has been thus withdrawn, first carries down both applying plates, they being held separated while within the coating substance in the tank, this 45 preventing interference with the taking on of a comparatively heavy layer over their adjacent faces. The pressure member rises 50 to its initial position, and the plates, after their immersion, are returned to normal, the lower remaining in the coating substance, and the upper being above the work-supporting surfaces. The apparatus is now in condition for the succeeding operation.

Having described my invention, what I claim as new and desire to secure by Letters Patent of the United States is:

65 1. A coating apparatus comprising a recep-

tacle for a coating substance, a pair of applying members movable into and out of said receptacle and arranged for contact with opposite sides of the work, and means for moving the members into and out of the substance constructed and arranged to hold the members separated from each other while within the coating substance in the receptacle and in the position out of the receptacle then to move them into contact with an interposed piece of work. 70

2. A coating apparatus comprising a receptacle for a coating substance, coacting applying members mounted for movement into and out of said receptacle and arranged for contact with opposite sides of the work, means for moving the members into and out of the substance constructed and arranged to hold the members separated from each other while within the coating substance in the receptacle 80 and in the position out of the receptacle then to move them into contact with an interposed piece of work, a scraper mounted upon the receptacle adjacent to the coating members, and means for pressing a work piece against said scraper during recessional movement of an applying member. 85

3. A coating apparatus comprising a receptacle for a coating substance, overlapping reciprocating applying members arranged for contact with opposite sides of a piece of work, means for moving one of the members into and out of the coating substance, and means for moving the other member into and out of the coating substance in time relation to the movement of the first-mentioned members, thereby to hold the members separated from each other when within the coating substance. 95

4. A coating apparatus comprising a receptacle for a coating substance, reciprocating applying members arranged for contact with opposite sides of a piece of work, movable means for supporting one of the members for movement into and out of the coating substance, movable means for supporting the other member for movement into and out of the coating substance, and a common actuator for said means arranged to move the members at different rates thereby to hold the members 100 separated from each other when within the coating substance. 110

5. A coating apparatus comprising a receptacle for a coating substance, two oscillatory arms mounted upon the receptacle, opposite overlapping applying members one carried by each arm, and means individual to each arm for moving the member which it carries into and out of the receptacle and into engagement with a piece of work. 120

6. A coating apparatus comprising a receptacle for a coating substance, two oscillatory arms pivoted upon the receptacle, overlapping applying members one carried by each arm for application to opposite sides of 130

a single piece of work, and a rotatable actuating member for each arm moving said applying members into and out of the receptacle and into contact with a piece of work.

5 7. An apparatus for coating stiffening pieces for the toes of shoes comprising a tank for a thermoplastic substance, a spindle mounted upon the tank, two arms arranged to turn about said spindle, an applying plate

10 carried by each arm, said plates being arranged one above the other for contact with opposite sides of a piece of work, a power-shaft journaled adjacent to the receptacle, and cams fixed to the shaft and respectively 15 co-operating with the arms.

8. A coating apparatus comprising a receptacle for a coating substance, coating applying members movable into and out of the receptacle and into and out of contact with opposite sides of a piece of work, and a movable pressure member co-operating with said piece of work.

9. A coating apparatus comprising a receptacle for a coating substance, coating applying members movable into and out of the receptacle and into and out of contact with opposite sides of a piece of work, a movable pressure member co-operating with the work, means for moving the applying members oppositely toward the work, and means for moving the pressure member in the same direction as one of the coating members into engagement with the work.

10. A coating apparatus comprising a receptacle for a coating substance, applying members movable into and out of the receptacle and arranged for contact with opposite sides of the work, a movable pressure member cooperating with the work, and a common 25 means for holding the applying members separated from each other while within the coating substance in the receptacle, for moving the members into and out of the substance and in the last-mentioned position into contact with an interposed piece of work and for moving the pressure member into and out of contact with the work, said means being constructed and arranged to maintain the contact of said pressure member with the 30 work after the withdrawal of the applying members from the work.

11. A coating apparatus comprising a receptacle for a coating substance, oscillatory arms mounted upon the receptacle, opposed 35 applying members for simultaneous application to opposite sides of a piece of work carried by two of the arms, a pressure-bar carried by a third arm, and means individual to each arm for moving the applying members into and out of the receptacle and the pressure member into and out of engagement with the work in predetermined sequence.

12. An apparatus for coating stiffening pieces for the toes of shoes comprising a tank for a thermoplastic substance, a spindle

mounted upon the tank, arms arranged to turn about the spindle, applying plates carried by two of the arms, said plates being arranged one above the other for application to opposite sides of a piece of work, a pressure-bar carried by a third arm, a power-shaft journaled upon the tank, and cams fixed to the shaft and respectively cooperating with the arms.

13. In a coating apparatus, a receptacle for a coating substance, said receptacle having a surface arranged to support a work-piece with a portion overhanging the receptacle, and opposite applying members movable into and out of the coating substance in the receptacle and into contact with opposite sides of the work supported upon the receptacle.

14. In a coating apparatus, a receptacle for a coating substance, said receptacle having a surface arranged to support a work-piece with a portion overhanging the receptacle, a scraper mounted upon the receptacle, and opposite applying members movable adjacent to the scraper into and out of the coating substance in the receptacle and into contact with opposite sides of the work supported upon the receptacle.

15. In a coating apparatus, a receptacle for a coating substance, said receptacle having a surface arranged to support a work-piece with a portion overhanging the receptacle, opposite applying members movable into and out of the coating substance in the receptacle and into contact with opposite sides of the work supported upon the receptacle, and a scraper mounted upon the receptacle between the supporting surface and applying members.

16. In a coating apparatus, a receptacle for a coating substance, said receptacle having a surface arranged to support a work-piece with a portion overhanging the receptacle, opposite applying members movable into and out of the coating substance in the receptacle and into contact with opposite sides of the work supported upon the receptacle, and a pressure member movable against the supported work.

17. In a coating apparatus, a receptacle for a coating substance, said receptacle having a surface arranged to support a work-piece with a portion overhanging the receptacle, a scraper mounted upon the receptacle, opposite applying members movable into and out of the coating substance in the receptacle and into contact with opposite sides of the work supported upon the receptacle, and a pressure member movable against the supported work above and in vertical alinement with the scraper.

18. A coating apparatus for applying a coating substance to work pieces having convex forward edges, comprising a tank for a coating substance, said tank being provided with a surface arranged to sup-

port a work-piece, there being a recess in the tank-wall adjacent to the supporting surface, and applying members movable into and out of the tank and having concave edges adjacent to the recessed wall.

19. A coating apparatus for applying a coating substance to work pieces having convex forward edges, comprising a tank for a coating substance, said tank being provided with a surface arranged to support a work-piece, there being a curved recess in the tank-wall adjacent to the supporting surface, applying members movable into and out of the receptacle and having concave edges adjacent to the recessed wall thereby to coat crescent-like areas on said pieces, and heating means associated with the tank.

20. In a coating apparatus, a receptacle for a coating substance, said receptacle having a surface arranged to support a work-piece with a portion overhanging the receptacle, a gage member situated outside a wall of the receptacle, and opposite applying members movable into and out of the coating substance in the receptacle and into contact with opposite sides of the work supported upon the receptacle.

21. A coating apparatus comprising a tank for a coating substance, said tank being provided with a surface arranged to support a work-piece, there being a recess in the tank-wall adjacent to the supporting surface, gage members situated at opposite sides of the recess, and applying members movable into and out of the tank adjacent to the recessed wall.

22. A coating apparatus comprising a tank for a coating substance, applying members movable into and out of the coating substance and into contact with opposite sides of the work, a shelf at the front of the tank, a gage member mounted upon the shelf and provided with a series of connected openings, and a pin yieldable upon the shelf and arranged to occupy any one of the openings.

23. An apparatus for coating stiffening pieces for the toes of shoes comprising a tank for a thermoplastic substance, applying members movable into and out of said substance and into contact with opposite sides of the stiffening pieces, shelves at the front of the tank arranged to support opposite edges of the stiffening pieces, and a gage member adjustable upon each shelf and arranged to locate the stiffening pieces with respect to the applying members.

24. A coating apparatus comprising a receptacle for a coating substance, an applying member movable into and out of the receptacle and into and out of contact with the upper side of a piece of work supported on the receptacle, a movable pressure member cooperating with the upper side of the work, and means for heating said pressure member.

25. In a coating apparatus, a frame com-

prising a receptacle for a coating substance, three oscillatory arms mounted upon the receptacle, opposite overlapping applying members carried by two of the arms for coating opposite sides of a piece of work, a pressure member carried by the third arm and positioned to clamp the piece of work against the frame, and a heating unit mounted upon the arm of the pressure member.

In testimony whereof I have signed my name to this specification.
